UNITED STATES PATENT OFFICE

AUGUST DURST, OF FREIBURG, GERMANY

SPARKING PLUG CONTROLLING DEVICE FOR INTERNAL COMBUSTION ENGINES

Application filed August 27, 1930, Serial No. 478,155, and in Germany September 14, 1929.

This invention relates to a sparking plug controlling device for internal combustion engines, which can be used especially for motor cars, aeroplanes, tractors and the like.

5 The invention differs from the known arrangements of this type, which consist chiefly of illuminating lamps arranged at a distant point and connected with the sparking plug by cables and the like, and which lamps can be switched in and out by a common switch, in that on the one hand the counter contacts are yieldingly inserted and at the same time form the seat for the illuminating lamps which on the other hand are pressed onto their seat by means of springs which serve at the same time either directly or indirectly for resiliently influencing the shiftable counter contacts.

20 A further improvement consists in that the inspection apertures in the base plate are made slot like and, through suitable thickness of the base plate and of the wall of the block accommodating the illuminating lamps, are so deep that a darkened room is produced, 25 which enables the illuminating of the lamps to be easily seen, even in day light.

An embodiment of the invention is illustrated by way of example in the accompanying drawing in which one control device is provided for a plurality of sparking plugs and can be switched in by a common switch.

Fig. 1 shows a front elevation and

Fig. 2 a rear view, partly in section, whereas

35 Fig. 3 is a vertical section on line III—III of Fig. 1.

From the drawing it will be seen, that on a base plate *a* the block *c* of hard rubber or the like, having bores *b* is arranged. These 10 bores *b* are narrowed at the lower end, a contact pin *d* provided with a head projecting through each narrowed end. An illuminating lamp *f* sits on each of these contact pins *d* and is pressed thereon by means of a spring *g*. The upper ends of the bores *b* are closed by a cover plate *h*. On each side of the block *c* a guide rod *i* is provided serving as guides for a switch element *k*. This latter is held, in inoperative position, away from the contact pins *d* by springs *m*. The switch ele-

ment *k* carries counter contacts *n* and terminal screws *o* for the cables leading from the sparking plugs. In order that the cables can be led to the terminal screws *o* arranged inside the switch element *k*, this latter is provided with apertures *p*. In order to raise the switch element *k*, and thereby bring the device into the operative position, a cam disc *q* is arranged rotatable under said element and adapted to be turned by a knob *r* from the front side of the device. The base plate *a* and the block *c* are each provided on each bore, at the point where the illuminating lamp is arranged, with a window *s*, so that the lighting up of the lamp can be observed from the front side of the apparatus at each ignition. The base plate *a*, owing to its thickness, produces the necessary darkening space to enable the illumination to be easily observed even in day light.

20 In the normal position the contact between the sparking plug and the control device is interrupted. If the engine is not working properly, and if it is supposed that one of the 25 sparking plugs is failing, the switch knob is rotated through about 90°, and the contact with the controlling device closed. Thus 30 each ignition in the engine is visible on the controlling device through the lighting up of the illuminating lamps. When the defect 35 has been removed, the driver can again switch out the controlling device by turning back the switch knob *r*.

The chief advantages of this new sparking plug controlling device consist in that 40 through the use of a common switching element in any cases, even if the contact pins are of unequal length or project unequal distances, a secure contact is established at all 45 contact points, and a mutual influencing of the illuminating lamps is prevented, and that 50 moreover by the special construction of the slots they form darkening chambers, which 55 facilitate the observing of the illumination 55 of the lamps in the day time, as also under 60 the most unfavourable circumstances even if the sun shines on the apparatus a heavy 65 shadow is produced in the slot which is then 70 lightened by the lighting up of the lamp.

I claim:—

1. A sparking plug controlling device for internal combustion engines, comprising in combination with a block of insulating material having bores, illuminating lamps inserted one in each of said bores, slideable contacts one in each bore and projecting therefrom adapted to support said illuminating lamps, springs one in each of said bores adapted to press said lamps against said slideable contacts, guide rods extending one on each side beyond the end of said block parallel to said lamps, a switch element guided on said rods, counter contacts on said switch element one opposite each of said contacts each adapted to be connected to a sparking plug, a switching device adapted to shift said switch element on said rods so that said contacts bear against said counter contacts and switch in said lamps, and a spring on each of said rods adapted to push said switch element away from said block and to break the contact between said contacts and said counter contacts.
2. A sparking plug controlling device as specified in claim 1 comprising in combination with the illuminating lamps and the block provided with bores for accommodating said tubes and having slot like inspection apertures communicating with said bores, a base plate with slot like apertures registering with the slot like apertures in said block, the apertures in said block and in said base plate forming a deep darkened space so that the lighting up of said lamps can be easily seen even in daylight.

In testimony whereof I affix my signature.
AUGUST DURST.
